SELF-THREADING SHUTTLE

Joseph B. Plevyak, Newton, N. J.

Application June 26, 1941, Serial No. 399,881

10 Claims. (Cl. 139—214)

My invention relates to weavers' shuttles, and more particularly to means for automatically re-threading the shuttle tensioning device when a new bobbin is placed in the shuttle.

The main object in view is to provide a device of this character so constructed that when a new bobbin is inserted in the shuttle for thread replenishment, the drag on the thread at the first pick of the shuttle thereafter, will automatically effect the proper placing of the thread in the tensioning devices, so that the weaving proceeds without interruption.

A minor object is to provide means for utilizing the drag upon the trailing end of the thread during said first flight, to effect the above automatic operation.

A third object subsidiary to said minor object just mentioned, is to provide a preliminary tensioning device located between the bobbin and the regular tensioning device, whereby to offer sufficient resistance to said drag on the free end of the trailing thread during the first pick of the shuttle after replenishment, to reliably effect said tension-threading operation.

A further very important object is to automatically relieve the thread from said preliminary tensioning thereon, when the regular tensioning device has become threaded.

A still further object is to obtain the above results, by means of a simple and cheap construction having few parts easily manipulated, not liable to get out of order, and easily replaced when worn out.

Other objects will be noted in the subjoined description.

A leading feature of the invention consists of a pair of adjustable pressure plates located in the throat of the thread-slot, between which plates the thread is passed immediately after leaving the bobbin, and before it reaches the regular tensioning devices, which devices have associated therewith a shelving portion composed of a series of fingers spaced slightly below the main thread slot of the shuttle, and projecting over the recess of the shuttle in which the regular tensioning devices are housed, said shelving fingers being arranged to cooperate with the tensioning devices to automatically direct the thread into operative relation with said devices upon the first pick of the shuttle after thread replenishment.

The invention consists in certain novel features of construction and relative arrangement of parts, as will be hereinafter described and

claimed, reference being had to the accompanying drawings, in which—

Fig. 1 is a broken view of a top plan of a shuttle provided with my improvements, a portion of the top of the shuttle being removed to disclose the tensioning devices.

Fig. 2 is a similar top plan view with the cover in place on the shuttle; whereby to clearly show the main thread slot of the shuttle, and the preliminary tensioning device.

Fig. 3 is a cross-sectional view of the shuttle, showing in particular, an end view of the preliminary tensioning device.

Fig. 4 is a broken longitudinal section of the shuttle, showing a side view of said device.

Fig. 5 is a broken longitudinal section of a shuttle showing a side elevation of the regular tensioning devices therein.

Fig. 6 is a fragmentary view on an enlarged scale, showing the relative position of the parts of the tensioning device when the shuttle is in operation.

Fig. 7 is a similar view showing the relative position of said parts of the tensioning device after the shuttle has started on its first flight after thread replenishment.

Fig. 8 is a perspective view on an enlarged scale, of the tensioning arm.

Fig. 9 is a perspective, on a somewhat enlarged scale, of the larger one of the two pressure plates which form the principal part of the preliminary tensioning device.

Fig. 10 shows in side elevation, the relative position of the preliminary tensioning device and the bobbin to each other.

Fig. 11 shows a top plan view of the preliminary tensioning device provided with means, controlled by the tension arm, for timing the releasing action of the preliminary tensioning device to correspond to the relative position of the tension arm.

Fig. 12 is a slightly modified form of the same.

Fig. 13 is an elevation on an enlarged scale of the outer side of the larger one of the pressure plates with the releasing lever carried thereby as shown in Fig. 12; and,

Fig. 14 is a perspective, on an enlarged scale, of the same with the releasing lever left off.

Referring further to the drawings, the numeral 1 indicates the shuttle, and 2 the removable portion of the cover thereof, which is secured on the shuttle by a screw 3. The bobbin is indicated by 4, the thread or yarn by 5, and the main thread-slot in the top of the shuttle by 6.

The removable cover 2 of the shuttle is recessed,

on its under side, as indicated in dotted lines in Fig. 2.

Special attention is now called to one of the leading features of the invention, namely; the preliminary tensioning device located in the throat of the shuttle, which, after a new bobbin has been introduced into the shuttle, grips the thread thereby causing additional resistance to its passage from the bobbin to the regular tensioning device; and during the first pick of the shuttle thereafter, utilizes the increased drag-tension thus imposed upon the thread, to operate the regular tensioning devices, and to direct the thread thereinto, and at that point, releases its grip on the thread and permits the regular tensioning devices to automatically move into relative tensioning relation to each other and to the thread, thereby leaving the preliminary tensioning device idle, and the regular tensioning devices in full control of the delivery of thread from the bobbin to the work, till such time as another bobbin is to be introduced into the shuttle; whereupon the above operation is repeated.

The preliminary tensioning device thus referred to, consists of two plates 7 and 8, the respective upper portions of which are yieldingly pressed into flat engagement with each other, to engage the thread which is passed between them preliminary to threading the regular tensioning devices of the shuttle. These plates are preferably pressed into engagement with each other by means of a coil spring 9 which is mounted in the side of the shuttle on the reduced inner end of a screw 10, as illustrated in Fig. 1; so that by a turn of the screw in one direction, or the other, the grip of the plates on the thread inserted between them is increased or diminished as may be desired. The plate 7 is slightly longer at its exit end than its mating plate 8, and this extended end is provided upwardly of its middle portion with a slight projecting portion 11 bent somewhat inwardly in the direction of the other plate. It will be noticed that the corners of this inwardly-turned projection are eased off or rounded, as indicated at 11a and 11b (see Figure 9). The special purpose of this projection with its rounded corners will be pointed out later.

The slightly shorter member 8 of the mating plates has an off-set portion 8a at its lower side (see Fig. 3), so that that portion cannot at any time come into flat engagement with the plate 7.

These mating plates 7 and 8 are provided near their lower edges with small bores 12 which are adapted to be loosely received upon pins 13 anchored in the shuttle on opposite sides of the thread slot near the bottom thereof (see Fig. 3).

As shown in Figs. 1 and 2, these mating plates are located at the entrance end of the thread slot, and are held in place by said pins 13, which in cooperation with the small bores 12 of the plates, act somewhat as hinges for holding the plates in proper operative relation to each other.

It will be noticed that the inner ends of the mating plates (the ends facing the bobbin), are sharply inclined outwardly from the top down as far as to the offset portion 8a of the shorter plate. The object of this inclination will be pointed out in describing the operation of the device.

The shuttle is provided with a recess 14 in which the main tensioning devices are located. The side 14a of this recess farthest from the tensioning bar is inclined outwardly at an angle to the main thread slot of the shuttle, and ex-

tends forwardly in the shuttle, and finally terminates in the usual thread-outlet opening 15 in the side of the shuttle near its forward end (see Fig. 1).

5 The portion of this recess immediately under the main thread slot 6 of the shuttle is provided with an overhanging shelf portion extending toward the wall 14a of the recess 14, but terminating a distance spaced therefrom about the width 10 of the main thread slot 6 of the shuttle. The upper ends of the regular tensioning posts 16 are anchored in this shelving portion near the forward edge of the same and in alinement with the wall 14a of the recess 14, while the lower ends 15 of these posts are anchored in the shuttle at the bottom of the recess, as illustrated in Fig. 5.

The tensioning bar 17 works on a pivot 18 suitably anchored in the shuttle, and is provided with thread hooks 19 extending forwardly-and-upwardly from the main bar 17, as more clearly shown in Fig. 8. This bar also has a short integral arm 20, extending outwardly from its pivot point 18; and attached to the upper end of this arm is a rubber band 21 arranged to pull in a direction 25 to operate the tensioning arm with its hooks 19. The outer end of this elastic band is secured to a screw 22 by means of an opening 23 in the screw, whereby when the screw is rotated, the tension on the band may be regulated.

30 The upper ends of the tensioning hooks 19 extend slightly above the plane of the overhanging shelf portion which is generally indicated by the numeral 24, and this overhanging portion is provided with runways 25 which permit 35 the upwardly extending tension hooks 19 to move to their normal tensioning position, as indicated in Figs. 1 and 6 of the drawings. The forming of the runways 25 in the overhanging shelf portion 24 forms the part of said portion immediately underneath said thread slot 6 into what 40 for convenience and brevity may be termed the fingers of the tensioning device, which fingers are indicated by 24a.

When a new bobbin has been placed in the shuttle for thread replenishment, and the shuttle 45 is picked, the drag on the thread first draws the thread between the two plates 7 and 8 of the preliminary tensioning device at the upper meeting edges of said plates. It will be seen from Fig. 1 of the drawings that the spring 9 which presses said plates together, is located near the exit end of the device, so that the insertion of 50 the thread between the plates at the flared entrance end of the device will be easily effected. The thread is drawn on down into the thread slot 6 and under the cover portion 2 thereof and falls upon the shelving portion 24 at the inner 55 side of the upturned hooks 19 of the tension arm, which hooks project upwardly through the runways 14 to a point above the plane of the shelving portion, as shown in Fig. 5. The end of the thread extends on out through the side delivery eye of the shuttle. The pull on the portion of 60 thread extending from the upper side of the projection 11a of the preliminary tensioning device to the side-delivery eye of the shuttle (see Figs. 1 and 9), tends to straighten this portion 65 of the thread, and in doing so, to slip it laterally outward over the shelving fingers 24a into the recess 14; but the upturned thread hooks 19 of the tensioning arm project upwardly through the runways 25 above the plane of the shelving portion as shown in Fig. 5, so that the thread in 70 its effort to slip over the ends of the fingers 24a engages the projecting upper ends of the tension 75

hooks 19 and forces them outwardly beyond the ends of said fingers into engagement with the wall 14a of the recess 14, as illustrated in Fig. 7 of the drawings, in which it is shown that the thread now extends in a straight line from the projection 11 of the preliminary tensioning device to the side delivery eye where it leaves the shuttle. The movement of the tension arm to this position is effected against the tension of the short elastic cord 21. The grip of the two plates 7 and 8 on the thread offers sufficient resistance to the movement of the thread to impart very considerable tension thereto; and the greater this tension on the thread, the greater is its inclination to straighten itself, by which latter act it moves the tension against the pull of the elastic band 21 to the position shown in Fig. 7. From this figure it will also be noticed that the drag-pull on the thread causes it to contact the thread-hook 19a at the outer end of the tension bar before it contacts the other thread hooks 19. This causes the force applied by the thread to the tension bar 17, to operate upon the same with maximum efficiency because the hook 19a is the hook farthest removed from the fulcrum 18 upon which the lever rocks. That the pull of the thread is greatest on the thread hook 19a at the outer end of the tension bar becomes more apparent when it is noted that at this point in the operation of the device the thread is in the position illustrated by the line 5-5 in Fig. 9 of the drawings. Special attention is called to the fact that at this point in the operation of the device, the thread is still pressed between the pressure plates 7 and 8 near their upper meeting edges with a marked downward-and-outward pull on the right-hand end of the thread; and with the downward movement of the thread between said pressure plates still obstructed by the projection 11 at the inner end of the plate 7, past which it has not yet escaped, all as indicated by the line 5-5 in Fig. 9 of the drawings, in which figure the thread (indicated by the line 5-5), has its right-hand end inclined considerably downward from the point where it is obstructed, or at least, retarded in its downward movement by the in-turned projection 11. This projection also serves to add somewhat to the resistance offered by the pressure plates to the forward movement of the thread before it has as yet been threaded into the regular tensioning device.

The upper corner 11a of this projection 11 is eased off, or slightly rounded, so that as the thread is progressively drawn forward over it, it will gradually work downwardly over said rounded corner by means of the downward pull on the right hand end of the thread; so that the projection 11 retards the downward movement of the thread between the pressure plates, and also somewhat increases the tension on the thread previous to the threading of the regular tensioning device, both of which are desirable up to this point in the operation of the device. But if this were continued indefinitely, it would hold the tensioning device in the position indicated in Fig. 7, and would thus defeat the ultimate purpose of the invention by preventing the tensioning device from at the proper time automatically assuming the position illustrated in Fig. 6 of the drawings, in which the tensioning mechanism is shown as properly threaded.

In order to proceed with the operation of the device after the parts have been successfully brought into the position indicated in Fig. 7, attention is now called to some very simple, and

yet very ingenious and effective means employed for this purpose: The respective upper portions of the pressure plates 7 and 8 which fit in flat engagement with each other, are inclined downwardly-and-outwardly at the entrance end of the plates, as indicated in Figs. 4 and 9; so that as the thread is drawn outwardly between said flat faces, the action of these inclined ends of the meeting plates tends to draw the thread downwardly as it advances between the plates. When the thread has reached the offset portion 8a of the plate 8, at the entrance end of the preliminary tensioning device, and has passed downwardly over the retarding projection 11 at the exit end of plate 7, it easily slips around the rounded corner 11a at the lower side of the projection 11, and suddenly drops into the ample open space 26 (between the two plates at their lower sides), and rests on the pins 13 which are anchored in the shuttle, and which hold the two plates in operative relation to each other, the plates having bores 12 into which the pins 13 are loosely received. The position of the thread at this time is indicated by the dotted lines near the lower side of Fig. 9 of the drawings. Just before the thread is drawn into this ample open space 26, the parts of the regular tensioning device are in the relative position to each other shown in Fig. 7, with sufficient tension exerted on the thread by the preliminary tensioning device to hold the parts in that position while the shuttle is in motion; but when the thread drops into the open space 26, the tension on the thread is gone, and the thread passes easily and freely through that open space, and the elastic band 21 suddenly brings the tension bar 17 to the position shown in dotted lines in Fig. 6, and the tensioning device is properly threaded. The fact that the two pressure plates 7 and 8 of the auxiliary tensioning device are spaced apart at their lower sides, causes the two plates to naturally lean toward each other and keep together at the top, aside from the pressure of the spring 9 operating to produce the same result.

From Fig. 10 of the drawings it will be seen that the thread in passing from the bobbin to the preliminary tensioning device is inclined upwardly, so that the tendency of the thread to straighten itself as it is fed from the shuttle to the work, exerts a lateral downward pull on the thread in addition to the downward tendency imparted to it by the incline of the meeting plates at their entrance end facing the bobbin. The result of this is that as soon as the forward pull on the thread as it is delivered by the shuttle to the work, drags it downwardly over the retarding projection 11, the thread quickly drops down into the ample space 26 at the lower side of the plates, as indicated by the dotted line. This space 26 is clearly illustrated in Fig. 3 of the drawings, which also shows the pins 13 upon which the thread rests when in this space.

As soon as the thread drops down into this space 26, it is relieved of the clamping pressure that had been imposed upon it by the meeting faces of the plates 7 and 8, and that in turn permits the tension bar 17 to be moved by the elastic cord 21 from the position shown in Fig. 7, to the position shown in Fig. 6, which threads the regular tensioning device, all of which has already been fully explained; but it will be seen that if the thread should be released from the grip of the preliminary tensioning device too soon, i. e., before the thread has been drawn over the ends of the shelving fingers 24a, and down into the

hooks 19, the tensioning devices will not be threaded when the tension bar 17 is swung inwardly by the elastic cord 21 as just described. However, the sooner the tension arm 17 is released after the thread has been drawn over the outer ends of the shelving fingers 24a the better it will be. But of the two, the premature release of the thread by the preliminary tensioning device would be much the worse. Therefore, to make it absolutely sure that the thread shall not be prematurely released by the preliminary tensioning device, I provide the modified means illustrated in Figs. 11 and 12. In Fig. 11, the tension bar 17a has an extension 27 at the left end thereof, which terminates in a short right-angled section 27a which normally takes through the two elongated registering openings 28 of the meeting plates 1 and 8. This opening is illustrated in Figs. 10, 13 and 14, and is just above the ample thread passage 26 at the lower side of the two plates, and the parts are all so arranged that the bent end 27a will positively prevent the downward passage of the thread into the thread passage 26 till such time as the tension bar 17a has moved into the position illustrated in Fig. 7, in which the thread has been drawn over the outer ends of the shelving fingers 24a and down into the thread hooks 19. Just at that point the section 27a will have been sufficiently withdrawn from the registering openings 28 to permit the thread to pass unobstructed into the thread passage 26 which, as already stated, is immediately underneath said openings, so that the threading of the main tensioning device immediately takes place, as has been already described above.

In Fig. 12 I have shown another very slight modification of the preliminary tensioning device in which I have shown the pressure plate 7 provided with a struck-out ear 29 upon which is rotatably mounted a spring-pressed lever 30 having a short right-angled section 31 corresponding to the similar section 27a in Fig. 11. This lever 30 has, at its outer end, a short slightly out-turned section 32 terminating in a right-angled bend 33 (see Fig. 13), extending into the path of the tension bar 17a as it moves to the position illustrated in Fig. 7. In this modification, the tension bar 17a, when depressed to the position shown in Fig. 7, will have sufficiently withdrawn the section 31 from the registering openings 28 of the meeting plates 1 and 8 to permit the unobstructed passage of the thread into the thread passage 26, as has already been described in regard to the section 27a in Fig. 11.

The spring which presses the lever 30 is indicated in Fig. 13 by the numeral 34.

The operation of the device has been fully described as the description proceeded.

From the foregoing, it will be seen that I have provided a device of great simplicity, and very effective in operation; with no parts easy to get broken or out of order; and all cheaply replaceable when worn out.

What I claim as new and desire to protect by Letters Patent is:

1. A loom shuttle having a bobbin chamber, a thread slot, and a tension chamber with spring-pressed tensioning mechanism therein, and a side delivery eye, the thread from the bobbin passing into and through the shuttle in contact with the tensioning mechanism, and emerging therefrom through the side delivery eye; and means contacting the thread between the bobbin and the tensioning devices for temporarily

resisting the movement of the thread from the shuttle to the tensioning devices; and means rendered effective by a pull on the free end of the thread against said temporary resistance, for opening the tensioning devices and laying the thread therein; and additional means for, at that point, freeing the thread from said temporary resistance, whereby to permit the return of the spring-pressed tensioning devices to their normal position, thereby threading the shuttle.

2. A loom shuttle having a bobbin chamber, a thread slot, and a tension chamber with spring-pressed tensioning devices therein; and a side delivery eye opening out from said tension chamber; said shuttle being arranged for the passage thereto of a thread from the bobbin chamber entering the shuttle through the thread slot and passing out through the side delivery eye, said tensioning devices including transversely disposed shelving fingers underneath the thread slot extending between the same and the tension chamber and terminating short of the wall of said chamber, whereby to leave a space at the top of said chamber at one side thereof uncovered by said shelving fingers for the eventual downward passage therethrough of the thread into the tension chamber below, said fingers having runways between them; and said tensioning device in the tension chamber below having thread hooks extending upwardly through said runways above the plane of the shelving fingers; and means rendered effective by a pull on the free end of the thread during a fraction only of the time required to complete the first flight of the shuttle after thread replenishment for moving the thread over the ends of the free ends of the shelving fingers into the full control of the tensioning devices in the chamber below, to be acted upon by said devices.

3. In a device of the character described, a preliminary tensioning device for the thread located in the throat of the thread slot of the shuttle and comprising two plates having their upper portions adapted to fit in flat engagement with each other, and their lower portions spaced apart a material distance, the extent of the meeting faces of said upper portions in the direction of the longitudinal travel of the thread being materially greater than their vertical extent from top to bottom, whereby a section of thread of material length is always in progressive engagement with said meeting faces as the thread passes between them; means at the upper part of the exit portion of said meeting faces for progressively flexing the thread as it passes from between the plates whereby to initially increase the tension on the thread as it passes from the plates to the main tensioning device, said plates having pairs of aligned bores in their lower spaced apart portions, and transverse pins passing loosely through said pairs of aligned bores with their outer ends anchored in the shuttle, the entrance end of the device, from its top down to the point where its sides are spaced apart, being inclined downwardly and outwardly, said device being designed to have its two upper portions spring-pressed toward each other whereby to adjust the gripping power of said plates on the thread, the spring being designed to adjustably press the plates near their exit ends whereby to adapt their entrance ends to be more easily spread apart for the initial entrance of the thread thereto.

4. In a device of the character described, a preliminary tensioning device for the thread de-

signed to be located in the throat of the thread slot of the shuttle, and comprising two plates having their upper portions adapted to fit in flat engagement with each other, and their lower portions spaced apart a material distance, said plates having pairs of aligned bores in their lower spaced portions, and transverse pins passing loosely through said pairs of aligned bores with their outer ends anchored in the shuttle, the entrance end of the device from its top down to the point where its sides are spaced apart, being inclined downwardly and outwardly, said device being designed to have its two upper portions spring-pressed toward each other, whereby to adjust the gripping power of said plates on the thread, the spring being designed to adjustably press the plates near their exit ends, whereby to adapt their entrance ends to be more easily spread apart for the initial entrance of the thread thereinto, one of said plates being slightly longer than the other and having near its upper side a short inwardly bent section with rounded corners for engaging the thread at its upper side and retarding the downward movement of the advancing thread as it works its way downwardly toward the open space between the plates.

5. In a device of the character described having tensioning devices including a spring-pressed tension bar, a preliminary tensioning device for the thread designed to be located in the throat of the thread-slot of the shuttle, and comprising two plates having their upper portions adapted to fit in flat engagement with each other, and their lower portions spaced apart a material distance, said plates having pairs of aligned bores in their lower spaced portions, and transverse pins passing loosely through said pairs of aligned bores with their outer ends designed to be anchored in the shuttle, said device being designed to have its two upper portions adjustably spring-pressed toward each other whereby to adjust the gripping power of said plates on the thread, the spring being arranged to press the plates near their exit ends, whereby to adapt their entrance ends to be more easily spread apart for the initial entrance of the thread thereinto, said plates having a pair of registering openings at the lower sides of their meeting faces just above the open thread space at the bottom of the plates; and a stop pin arranged to pass into and out of said openings to alternately open and close the downward passageway between the two plates, said stop pin being correlated to the spring-pressed tension bar of the shuttle to move synchronously therewith, and arranged to withdraw said pin from said registering openings when the tension bar is moved into position to open the tensioning devices for the reception of the thread thereinto, and to return the pin into said openings when the tension bar is moved to its normal thread tensioning position, whereby when the tension bar is moved into position to open the tensioning devices, the passageway between the plates is opened for the thread to be passed downwardly between them into the open thread space below, thereby relieving the tension imposed upon the incoming thread when pressed between said plates, and permitting the tension bar to return by its own spring pressure to its normal tensioning position, and thus leaving the regular tensioning device in full control of the thread as it is fed to the work.

6. In a self-threading shuttle having a main tensioning device including a spring-pressed tension bar movable into tensioning and non-ten-

sioning position, and standing normally in tensioning position, a preliminary tensioning device located between the bobbin and the main tensioning device; and intermediate mechanism between said spring-pressed tension bar and said preliminary tensioning device for correlating the movements of the two tensioning devices, whereby the movement of the main tension bar into non-tensioning position operates to open the preliminary tensioning device for the passage of thread downwardly therethrough also into non-tensioning position, and the movement of the tension arm to tensioning position closes the preliminary tensioning device against the downward passage therethrough of thread to non-tensioning position.

7. In a device of the character described, the combination with a main tensioning device, of an auxiliary tensioning device comprising two plates located between the bobbin and the main tensioning device, and having at their upper portion smooth flat faces adapted to meet in face-to-face engagement with each other, the device being adapted to receive the thread at its upper edge between said flat faces, said plates being spring-pressed toward each other to cause them to yieldingly grip the thread as it passes between them from the bobbin to the main tensioning device, and having their edges, which face the bobbin, inclined downwardly and outwardly, whereby to impart to the thread a tendency to feed downwardly as it is drawn between the plates in passing from the bobbin to the main tensioning device, the opposing sides of said plates, immediately beneath these meeting faces, being spaced apart to form an ample passageway for the thread after it has fed downwardly therewith from between the meeting faces at the upper sides of the two plates, said meeting plates, just above said ample passageway for the thread, being provided with means for blocking the downward passage of the thread between said plates till a predetermined point has been reached in the operation of the main tensioning device, and for opening said passageway when another predetermined point in the operation of the main tensioning device has been reached.

8. In a device of the character described, the combination with a main tensioning device, of an auxiliary tensioning device comprising two plates located between the bobbin and the main tensioning devices, and having at their upper portions smooth flat faces adapted to meet in face-to-face engagement with each other, the device being adapted to receive the thread at its upper edge between said flat faces, said plates being spring-pressed toward each other to cause them to yieldingly grip the thread as it passes between them from the bobbin to the main tensioning device, and having their edges, which face the bobbin, inclined downwardly and outwardly, whereby to impart to the thread a tendency to feed downwardly as it is drawn between the plates in passing from the bobbin to the main tensioning device, the opposing sides of said plates, immediately beneath these meeting faces, being spaced apart to form an ample passageway for the thread after it has fed downwardly therewith from between the meeting faces at the upper sides of the two plates, said meeting plates, just above said ample passageway for the thread being provided with means for positively opening and closing the passageway between said plates when respective predetermined points have been

reached in the operation of the main tensioning device, the extent of the meeting faces of said upper portions of the auxiliary plates in the direction of the longitudinal travel of the thread being materially greater than their vertical extent from top to bottom, whereby a section of thread of material length is always in progressive engagement with said meeting faces as the thread passes between them.

9. In a self-threading shuttle, a draw-back tensioning device having a member movable in one direction into its open position for the reception of the thread, and in the opposite direction into its operative position for tensioning the same, said member being spring-pressed in a direction to hold it normally in its tensioning position; and means actuated by the initial movement of the first pick of the shuttle after thread replenishment for temporarily tensioning the thread, and by virtue of such tension for moving said

member from its normal tensioning position into its open thread-receiving position.

10. A self-threading shuttle having a draw-back tensioning device, and an auxiliary device for rethreading the same after thread replenishment, said rethreading device comprising two vertically disposed plates having their upper portions yieldingly held in face-to-face engagement with each other with the thread passing between them, the edges of said upper portions of the plates facing the bobbin being inclined downwardly and forwardly, and the extent of the meeting faces of said upper portions of said plates in the direction of the longitudinal travel of the thread being materially greater than their vertical extent from top to bottom, whereby a section of thread of material length is in progressive engagement with said meeting faces as the thread passes between them.

20

JOSEPH B. PLEVYAK.
